UNITED STATES PATENT OFFICE.

JOHN W. SAGER, OF CICERO, ILLINOIS, ASSIGNOR TO WESTERN ELECTRIC COMPANY,
INCORPORATED, OF NEW YORK, N. Y., A CORPORATION OF NEW YORK.

TUBE-ROLLING MACHINE.

1,293,940.

Specification of Letters Patent. Patented Feb. 11, 1919.

Application filed August 10, 1916. Serial No. 114,241.

To all whom it may concern:

Be it known that I, JOHN W. SAGER, a citizen of the United States, residing at Cicero, in the county of Cook and State of Illinois, 5 have invented certain new and useful Improvements in Tube-Rolling Machines, of which the following is a full, clear, concise, and exact description.

This invention relates to a tube rolling 10 machine, and more particularly to a machine of this kind in which the tubes are spirally constructed by rolling a flat piece of material about a cylindrical mandrel.

The object of this invention is to provide 15 an improved, economical, and efficient machine for rolling tubes in which the tube is spirally constructed on a rotatable mandrel and in which the layers at each end of the spiral tube are glued to their superimposed 20 layers.

The invention is illustrated in the accompanying drawings in which:

Figure 1 is a front elevation of the complete machine;

25 Fig. 2 is an end elevation of the right side of the machine;

Fig. 3 is a vertical section on the plane 3-3 of Fig. 1 looking in the direction of the arrows;

30 Fig. 4 is a fragmentary front elevation with the paper gage and pasting leaves turned down;

Fig. 5 is a plan view of the power transmitting means with the housing broken 35 away;

Fig. 6 is an end view of the clutch mechanism;

Fig. 7 is a front elevation of an auxiliary fixture for curling the ends of the paper 40 before they are inserted in the tube rolling machine;

Fig. 8 is an end elevation of this fixture, and

45 Fig. 9 is a plan view of the mandrel bearing.

The various operating parts of the machine are mounted on a cast housing which consists of the side walls 6 and 7 and the front and rear walls 8 and 9 respectively.

50 Each of the side walls is fitted with a slotted bearing in which is journaled the rotatable mandrel 10. Slidably mounted on suitable shoulders on each of the side walls 6 and 7 is the plate 11, the front end of which has a

55 concave surface the curvature of which is the same as the convex surface of the rota-

table mandrel 10. The movement of the 60 slideable plate 11 is controlled by the lever arm 12 which is pivotally mounted on the rear wall 9 of the housing by means of the pin 13 which is yieldably mounted in the slot 14 of the rear wall 9 by means of the spiral spring 15. The link 16 is pivotally mounted on the lever arm 12 at 17 and to the 65 upwardly extending shoulder 18 of the slideable plate 11 at 19. Consequently when the lever arm 12 is moved toward the front of the machine the horizontal portion of the lever arm 12 and the link 16 will tend to assume the horizontal position illustrated in 70 Fig. 3, and will thereby move the slideable plate 11 toward the front of the machine and in contact with the mandrel 10. The top surfaces of the side walls 6 and 7 of the housing contain the upwardly projecting 75 lugs 21 and 22 respectively. In these lugs are mounted the brackets 23 and 24 in which is loosely journaled the rotatable roller 25. Pivotally attached to the right bracket 23 is the link 20, the lower end of which is pivotally attached to the upper end of the link 30 by the pin 26, the lower end of the link 30 being attached to the housing by means of the pin 27. By means of this lever movement attached to the side of the housing the 80 roller can be lowered so that its surface will come into contact with the surface of the mandrel 10 when the link 20 of the lever 85 movement is thrown forward. Pivotally mounted on each side of the housing 6 and 7 are the levers 28 and 29 respectively. These 90 levers are pivoted at about the center line of the machine, as shown in Fig. 3, and the rear ends of these levers are pivotally connected to upwardly extending links 32 and 95 34 respectively. The links 32 and 34 are pivotally secured to arms extending rearwardly from the horizontal plate 35, the plate 35 being pivotally mounted on the 100 rearward end of the lugs 21 and 22 on the forward end of which are pivotally mounted the arms 23 and 24 respectively. The links 105 of this lever movement are pivoted and interconnected so that when the cylindrical rod 38, which interconnects the front ends of the two links 28 and 29, is depressed the rear ends of the links 28 and 29 are moved up and through the interconnecting links 32 and 34, the plate 35 is swung about its pivot, and the stretcher bar 39 attached to the 110 front end thereof is moved down into contact with its component stretcher bar 40.

The bar 39 is mounted in the plate 35 by means of the pins or plungers 52 and 53 which are yieldingly held in cavities in the plate 35 by means of the spiral springs such as 54. The bar 40 is securely attached to the brackets 42 and 43 which are pivotally mounted in the slide plate 11 and yieldingly held by the springs 45 and 46. The function of the bars 39 and 40 is to tension the paper 10 to be used in making the tube after it has been placed on the mandrel 10 and the slide plate 11 has been moved forward by means of the lever arm 12 so that the paper is rigidly held between the front end of the 15 slide plate 11 and the mandrel 10. The paper 41 is then inserted between the bars 39 and 40 as illustrated in Fig. 3. When the paper is so placed between these two bars the cylindrical rod 38 at the front of the 20 machine is depressed, and this causes the dropping of the bar 39 which in its movement downward carries the bar 40 with it. The angle of contact between bars 39 and 40 is such that bar 39 is given a sliding movement 25 which causes it to recede slightly on the plungers 52 and 53 and as this movement is in a direction away from the mandrel 10, it tends to pull the paper tight against the surface of the cylindrical mandrel. The 30 movement of the plate 35 is controlled by springs such as 50 which cause this plate to assume its normal position as soon as the pressure is removed from the cylindrical rod 38.

35 The front plate 8 of the housing is equipped with the projecting lugs 55 and 56 between which is mounted the cylindrical rod 57. Mounted on said rod in the space between the inner surfaces of said lugs 40 is the plate or leaf 58 which may be swung around the rod 57 as an axis into the position shown in Fig. 3. The plate may also be swung about the rod 57 so that its surface rests below the rod 57 as shown in 45 Fig. 4. Mounted on the rod 57 at the outer surfaces of the lugs 55 and 56 is the cover plate or pasting leaf 60 which is pivotally mounted on the rod 57 as an axis and is capable of the same movement as the 50 plate 58. The plate 58 is equipped at its lower surface with a straight edge 61 which serves to act as a guide in lining up the paper when it is put on the mandrel 10 and thus serves as a means to start the paper 55 straight on the mandrel 10. The plate 60 is swung into position so as to cover the plate 58 when the paper has been placed on the mandrel 10 and properly trued up, at which time the paper is placed on the plate 60, 60 which plate serves as a base for holding the paper when the adhesive is applied thereto. Loosely mounted between the side walls 6 and 7 of the housing is the rod 64, in the center of which is attached the electrical 65 heating element 65. The lever arm 66 is securely fastened to the right end of the rod 64, said rod being revolved whenever the lever arm 66 is moved. Any movement of the rod 64 carries with it the electrical heating element 65. To the front end of the 70 electrical heating element 65 is attached the copper bar 68 which extends across the front surface of the machine between the side walls 6 and 7 and which contacts with the surface of the mandrel 10 when the front 75 end of the electrical heating element is tilted up by means of the movement of the lever arm 66. To the electrical heating element 65 is attached a cord 70 which may be connected to any suitable source of electrical 80 power for energizing the heating element.

Attached to the left side of the machine is the means for driving the mandrel 10 and its associated clutch mechanism. As indicated in Fig. 5, a disk 72 is attached to the 85 left end of the mandrel 10, the outer surface of which contains two cylindrical projecting lugs 73 and 74. Coöoperating with the disk 72 and the lugs 73 and 74 is the disk 75 which is likewise equipped with cylindrical 90 projecting lugs 76 and 77. The disk 75 is rigidly attached to the shaft 78, to the other end of which is attached the disk 79 equipped with the cylindrical projecting lugs 80 and 81. The shaft 78 is loosely fitted 95 in the hollow shaft 33 and the hollow shaft 33 is journaled in the bearings 82 and 83, between which is mounted the pulley wheel 84. Projecting from the end surface of the hollow shaft 33 are the lugs 61 and 62 which 100 coöperate with the lugs 80 and 81 to drive the shaft 78. The pulley wheel is completely covered by a suitable housing 85. Due to the cylindrical projecting lugs attached to the disks 79 and to the end of the shaft 33 it 105 will be evident that whenever any suitable means of power is applied to the pulley 84, the cylindrical projections on the disk 79 and the end surface of the shaft 33 will rotate between the same vertical planes and 110 consequently the lugs on the shaft 33 will engage those on the disk 79 and the rotation of the shaft 33 will be transmitted to the shaft 78. Since the disk 75 is rigidly secured to the end of the shaft 78, the lugs 76 115 and 77 thereon will coöperate with the lugs 73 and 74 on the disk 72 to transmit the rotation to the mandrel 10. It will likewise be obvious that when the projecting lugs on the disks 72 and 75 are so placed that a line interconnecting the lugs on the disk 75 is substantially at right angles to the line interconnecting the lugs on the disk 72, the mandrel 10 and its associated disk may be readily lifted from its bearings in the machine. 120 This arrangement is provided so that the tubes, after being rolled, may be readily slipped from the mandrel by completely removing the mandrel and tube from the machine. The left hand bearing of the man- 125 130

5 drel is equipped with a slot 88 which rides in a projection 86 in the lower surface of the bearing which prevents lateral shifting of the mandrel 10 when it is suitably placed 5 in position in its bearings. This is illustrated in Fig. 9.

Attached to the outer end of the driving shaft is a clutch mechanism which consists of the disk 79 which has attached to one of 10 its quadrants a braking member 91 equipped with the cam surface 90. The disk 79 is rigidly attached to the shaft 78 and the shaft 78 is slidably fitted in the hollow shaft 33. Registering with the end of the shaft 78 15 are the strong leaf springs 93 which are fastened to the lower end of the bearing bracket 95. Attached to the bearing bracket 95 is the bracket 96 in which is pivotally mounted the lever arm 97 to which is secured the rod 20 98 which tends to pull the lever arm 97 into the dotted position shown in Fig. 6 due to a spiral spring inclosed in the housing 99. Fastened to the lever arm 97 by means of the screw 98' is the chiseled edged cam stop 25 100 which registers with the inclined cam surface 90 of the disk 79 when the lever 97 is in the dotted position shown in Fig. 6. When in this position the inclined surface of the disk 79 will ride over the inclined 30 35 surface of the stop 100 and the shaft 78 will be forced out against the tension of the leaf springs 93. This will act as a brake on the shaft 78 which in turn will brake the shaft 33. Due to this braking action the belt 35 will slip over the surface of the pulley 84 and hence stop the rotation of the shafts 33 and 78 and the mandrel 10.

The lever 97 is normally held in its outer position by means of the lever 101 which is 40 equipped with a right angled slot which registers with the pin 102. This prevents the pulling of the lever 97 into its alternate position by the spring in the housing 99. When the lever 101 is thrown into its alternate 45 position, as is indicated by the broken lines, the right angle shoulder of the lever 101 is thrown out of the line of movement of the pin 102 and the rod 98 is free to move the lever 97 into the braking position.

50 In order to prepare the paper so that it will be suitable for rolling tubes on the machine an auxiliary curling fixture, shown in Figs. 7 and 8, is utilized. This fixture consists of a base plate 105 to each end of which 55 is secured a bracket such as 106 between which is mounted the metal plate 107. Secured to the front surface of the base plate 105 are the butt hinges 108 and 109, to the movable part of which is attached the plate 60 110. At either end of the plate 110 is an upwardly extending arm, 111 and 112 respectively, to the outer ends of each of which is secured a bolt, 113 and 114 respectively. These bolts extend through the brackets 65 which hold the plate 107 and are fitted at

their outer ends with a nut and washer, between which and the surface of the brackets holding the plate 107 are mounted spiral springs such as 115. These spiral springs serve to yieldingly hold the plate 110 against 70 the plate 107.

In the operation of the machine the paper which is to be rolled on the tube is first inserted between the plates 107 and 110 of the curling fixture shown in Figs. 7 and 8. This 75 is readily done by pulling the arm 112 out to the dotted position indicated in Fig. 8, slipping the paper between the plates and then allowing the plate 110 to assume its normal position. The paper will then be held in 80 the fixture as indicated by the broken line in Fig. 8. When the paper is in this position it is readily drawn from between the plates 110 and 107 over the edge of the plate 110 and in a direction substantially parallel to 85 the plane of this plate. This will give the edge of the paper a curvature so that it may be readily fitted around the mandrel 10 of the tube rolling machine.

When the paper has been thus curled, the 90 curled surface is placed around the mandrel 10 and the other edge of the paper is trued up with the straight edge 61 at the bottom of the gage leaf 58. The lever 12 is then drawn forward so that the slide plate 11 will 95 bend and firmly hold the curved surface of the paper against the mandrel 10 when a coating of adhesive is applied to the curled portion of the paper. The paper is then raised from the gage leaf 58, so that the 100 plate 60 may be swung into position, shown in Fig. 1, over the gage leaf 58. The paper is then laid on the plate 60 where the other end thereof is given a coating of adhesive 105 which is used to glue the layers of the paper tube together. After this the paper is removed from the plate 60 and placed over the edge of the stretcher bar 40. The cylindrical rod 38 is then depressed which causes the bar 39 to register with the bar 40 and these 110 two will then move in a direction away from the mandrel 10 and cause the paper to be drawn tightly against the surface of the mandrel. With the cylindrical rod 38 depressed so as to give the paper tension, the 115 lever arm 20 is moved forward so as to bring the roller 25 down so that it will ride on the surface of the paper contained on the mandrel 10, in which position the roller 25 serves to hold the paper in its stretched condition 120 after the rod 38 has been released.

The lever 97 is then actuated which releases the brake and permits the rotation of the mandrel 10. While the mandrel 10 is rotating the lever arm 66 is raised which 125 causes the heated bar 68, attached to the end of the electrical element 65, to ride on the surface of the tube after it is rolled. This materially aids in the drying of the adhesive which is used to glue together the superim- 130

posed layers which constitute the wall of the tube. The heating bar 68 in its upward movement strikes the under surface of the plate 58, and since the plates 58 and 60 are 5 constructed of comparatively light sheet metal, the momentum of the bar 68 is sufficiently great to swing said plates into their horizontal position thus automatically placing these plates into the initial position in 10 which they are used in the rolling of the next tube. When all the paper has been rolled on the mandrel and the heated bar 68 has been applied the roller 25 is returned to its upper position by means of the lever arm 15 20, and the slide plate 11 is moved back by means of the lever 12. The heated bar 68 will drop back to normal as soon as the upward pressure is removed from the lever handle 66. The rotating mandrel is then 20 stopped by operating the brake lever arm 101 which will hold the pulley 84 against further rotation by the belt.

The disk 72 is now rotated so that the cylindrical projections of this disk are so 25 aligned that the mandrel 10 may be readily removed without any interference from the cylindrical projections on the disk 75. The rolled paper tube which is slidably wound on the mandrel is then slipped therefrom 30 when the mandrel is returned to the machine and the above operations are repeated for the rolling of the next tube. As the tubes are slipped from the mandrel they may be inserted into closely fitting hollow tubes to 35 allow the adhesive to properly set.

Although the machine which is illustrated in the attached drawings and described in the foregoing constitutes the preferred embodiment of the invention, it will be quite 40 obvious that the invention is capable of many variations and applications without departing from its spirit and scope.

What is claimed is:

1. In a machine for rolling paper tubes, 45 the combination with a rotatable mandrel, of means for stretching the paper on said mandrel, means operable to engage the paper on said mandrel and hold it in the stretched condition after the stretching 50 means is released, and means coöoperating with said mandrel to tightly roll the paper in a tube about said mandrel.

2. In a machine for rolling paper tubes, 55 the combination with a rotatable mandrel, of means to fasten the end of the paper in a curve about said mandrel, means to stretch the paper about said mandrel, means operable to engage the paper on said mandrel and hold it in said stretched condition after 60 said stretching means is released, and means coöoperating with said mandrel to roll the paper in a tube about said mandrel.

3. In a machine for rolling paper tubes, 65 the combination with a rotatable mandrel, of means to fasten the end of the paper

about and hold it firmly pressed against said mandrel, means to gage the edge of said paper so it will roll straight about said mandrel, means to suitably hold the free end of said paper extending from said mandrel for the application of an adhesive, 70 means to stretch the paper about said mandrel, means to hold the paper in said stretched condition after said stretching means is released, and means to rotate said mandrel to form the paper into a tube. 75

4. In a machine for rolling paper tubes, the combination with a rotatable mandrel, of means whereby the end of the paper may be bent about said mandrel and firmly 80 pressed against the surface of said mandrel, means to gage the other end of said paper so it will roll straight about said mandrel, means to suitably hold the free end of the paper extending from said mandrel for the application of an adhesive, 85 means to stretch the paper about said mandrel, means to hold the paper in the stretched condition after said stretching means is released, means to rotate said mandrel to form the paper into a tube, 90 and means to heat the outer surface of said tube as it is revolved with said mandrel whereby the adhesive used to glue the superimposed layers of said paper will be rapidly dried. 95

5. In a machine for rolling paper tubes, the combination with a rotatable mandrel, of means whereby the end of the paper may be bent about said mandrel and firmly 100 pressed against the surface of said mandrel, means to gage the other end of said paper so it will roll straight about said mandrel, means to suitably hold the free end of the paper extending from said mandrel for the application of an adhesive, 105 means to stretch the paper about said mandrel, means to hold the paper in said stretched condition after said stretching means is released, means to rotate said mandrel to form the paper into a tube, an electrically heated means for heating the outer 110 surface of said tube as it is rotated with said mandrel whereby the adhesive used to glue the superimposed layers of paper will be rapidly dried, and bearing means in which said mandrel is revolved and held from longitudinal movement also having open upper portions to permit ready removal of the 115 mandrel so the tube may be slipped therefrom. 120

6. In a device of the character described, the combination with a rotatable shaft, of a rotatable mandrel, means for rotating said mandrel with said shaft, means whereby the end of a paper may be bent about said 125 mandrel and firmly pressed against the surface of said mandrel, means to stretch the paper about said mandrel, a roller coöperating with said mandrel for holding the paper in said stretched condition after the stretch- 130

ing means is released, a braking means controlling the rotation of said shaft, and means whereby said braking means may be released to rotate said shaft and said mandrel to 5 roll the paper in a spiral tube about said mandrel.

7. In a device of the character described, the combination with a rotatable shaft, of a rotatable mandrel, means for rotating said 10 mandrel with said shaft, a sliding plate the end surface of which may be pressed against the surface of said mandrel to hold the end of a curled paper between said mandrel and said plate, a gage plate for truing the free 15 edge of said paper so that the paper will roll straight about said mandrel, a cover plate which may be swung into position above said gage plate and which serves as a base plate for holding said paper for the 20 application of an adhesive, a stretcher bar located above and in parallelism with said mandrel, a second stretcher bar coöoperating with said first bar, means for operating said second bar whereby the paper will be 25 stretched between said mandrel and said stretcher bars, a roller coöoperating with said mandrel, means for moving said roller into operative relation with said mandrel whereby the paper will be held in said stretched 30 condition about said mandrel when said stretching bars are released, and means for controlling the operation of said shaft to control the movement of said mandrel for the rolling of paper tubes thereon.

35 8. In a device of the character described, the combination with a rotatable mandrel, of a slidable plate, means for moving said plate into contact with said mandrel whereby the end of a curled paper will be firmly 40 held between the end surface of said plate and the curved surface of said mandrel, a gage leaf provided with a straight edge for truing the paper on said mandrel, a pasting plate for covering said gage leaf and which 45 serves as a base plate for applying the adhesive to said paper, a stretcher bar mounted above and in parallelism with said mandrel, a second stretcher bar coöoperating therewith, means for operating said second 50 stretcher bar whereby the paper is stretched between said mandrel and said bars, a roller, means for moving said roller so that it will contact with the surface of said mandrel and hold the paper placed in position on said 55 mandrel in a stretched condition after said stretching bars are released, an energized heating bar, means to move said bar into contact with said paper tube after it has been rolled on the mandrel for the 60 purpose of drying the adhesive and bearing means for said mandrel from which said mandrel may be removed so that the paper tube can be readily slipped therefrom.

9. In a machine for rolling paper tubes, the combination with a rotatable mandrel, 65 of a slidable plate, means to operate said plate whereby the end of the paper may be firmly held between said mandrel and said plate, a stretching means mounted above and in parallelism with said mandrel, a rotatable 70 roller coöoperating with said mandrel, means to operate said roller so that it will hold the paper in said stretched condition after the paper stretching means is released, and means to rotate said mandrel to form the 75 paper into a tube.

10. In a machine for rolling paper tubes, the combination with a rotatable mandrel, 80 of a slidable plate operable to firmly hold the end of the paper between its end surface and said mandrel, a gage leaf fitted with a truing edge to gage the paper so that it will be rolled straight about said mandrel, a stretching means mounted above and in parallelism with said mandrel for stretching the paper between said stretching means and said mandrel, a rotatable roller coöperating with said mandrel, means to operate said roller so that it will hold the paper in 85 said stretched condition after the stretching means is released, and means to rotate said mandrel to form the paper into a tube.

11. In a machine for rolling paper tubes, the combination with a rotatable shaft, of a rotatable mandrel which may be rotated by 90 said shaft, means whereby a paper may be bent about said mandrel and tightly held against its surface, a stretching means for stretching the paper between said mandrel and said stretching means, a rotatable roller 95 coöperating with said mandrel, and means to move said roller in contact with said mandrel whereby the paper is tightly stretched about said mandrel when it is rotated by 100 said rotatable shaft.

12. In a machine for rolling paper tubes, the combination with a rotatable mandrel, of means to fasten the end of the paper about said mandrel, means for drawing said 110 paper taut before rolling on said mandrel, and means for holding said paper taut after said drawing means is released and during the entire rolling of said tube.

13. In a machine for rolling paper tubes, the combination with a rotatable mandrel, 115 of means to fasten the end of the paper about said mandrel, positive means for holding taut said paper during the entire rolling of said tube by said mandrel, heating means applicable at predetermined times to said 120 tube as it is rotated with said mandrel, and means for operating said heating means.

In witness whereof, I hereunto subscribe my name this 1st day of Aug. A. D., 1916.

JOHN W. SAGER.
